(57) **CLAIM**

The ornamental design for an artificial lash extension, as shown and described.

DESCRIPTION

FIG. 1 is a top left perspective view of an artificial lash extension in accordance with the claimed design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a top left perspective view of an artificial lash extension in accordance with the claimed design, wherein the break lines indicate indeterminate length.

FIG. 9 is a front view of thereof, wherein the break lines indicate indeterminate length.

FIG. 10 is a rear view thereof, wherein the break lines indicate indeterminate length.

FIG. 11 is a right side view thereof, wherein the break lines indicate indeterminate length.

FIG. 12 is a left side view thereof, wherein the break lines indicate indeterminate length.

FIG. 13 is a top view thereof, wherein the break lines indicate indeterminate length; and,

FIG. 14 is a bottom view thereof, wherein the break lines indicate indeterminate length.

The broken lines consisting of evenly spaced lines in the figures show portions of the artificial lash extension that form no part of the claimed design. The break lines that separate parts of the artificial lash extension represent indeterminate length and form no part of the claimed design.
